UNITED STATES PATENT OFFICE.

RUDOLF PFAFFENBACH, OF LEIPSIC, AND HERMANN MÜLLER, OF LEIPSIC-GOHLIS, GERMANY.

ELECTRICALLY-DRIVEN SUSPENDED RAILWAY.

No. 807,089.

Specification of Letters Patent.

Patented Dec. 12, 1905.

Application filed January 13, 1904. Serial No. 188,876.

To all whom it may concern.

Be it known that we, RUDOLF PFAFFENBACH, director, residing at 34 Pfaffendorferstrasse, Leipsic, and HERMANN MÜLLER, engineer, residing at 8 Ulanenstrasse, Leipsic-Gohlis, Germany, subjects of the German Emperor, have jointly invented new and useful Improvements in and Relating to Suspended Railways for Combined Electric and Hauling Traction; and we do hereby declare the following to be a full, clear, and exact description of our invention, such as will enable others skilled in the art to which it appertains to make and use the same.

Prior to our present invention it has been the general custom in raising loads from a lower horizontal level to a higher—as, for instance, from the ground plane to the charging-bell of a blast-furnace (and especially for heavier loads carried by conveying-cars)—to employ elevators or similar lifting devices, which have the great disadvantage that they work intermittently and require continuous attendance in shifting the conveyer-cars from the horizontal level to the elevator, and vice versa. The problem of substituting for these intermittently-operating vertical or inclined elevators a continuously-working system has been in part solved by the well-known inclines provided with a continuous rope or cable transmission, some of which have been extensively used by us. In such systems, however, the cable-car or suspended car must be pushed along by hand upon the horizontal level—for instance, when the latter has many curves or branches—and in this respect is like the ordinary conveyer-car or narrow-gage car. As against these expensive systems the present invention presents an arrangement for raising and lowering loads propelled electrically and individually along a horizontal level, which arrangement operates entirely automatically and continuously without necessitating the interruption even for a moment of the progress of the cars arriving at the lifting device. The problem presented is thus solved in a complete and simple manner by the arrangement constituting the subject-matter of the invention. The arrangement is such that an electrically-operated suspended railway which forwards the loads upon the horizontal levels is connected with the higher level to which the loads are to be transported by an incline adapted to be traversed by the

carriers (the driving-motor of the carriers being cut out) through the instrumentality of a hauling cable or chain ranged along the incline, with which the carriers as they arrive at the incline automatically couple by means of a suitable gripping device and from which in leaving the incline they automatically uncouple. By the combination of the electrically-driven suspended railway with the continuously-operating conveyer, located at the interposed incline, and the automatic coupling and uncoupling of the suspended carriers a continuous and entirely automatic elevating system is obtained, combined with a similarly satisfactory horizontal system.

We are aware that it has been proposed to assist tramway-vehicles in overcoming inclines by providing thereat a conveyer which draws the vehicle up the inclines. Aside from the difference of the problems involved, however, the present invention, contrary to the tramway, requires the employment of an electrically-driven suspended railway, which is essential as an element of the combination. The more frequently occurring heavy inclines met with in putting the invention into practical use could not be traversed by the tramway-cars, because tramway-cars, in consequence of the invariable location of their centers of gravity, would tip rearwardly or forwardly, according to where they were engaged by the traveling conveyer. This would be especially the case if the wheels of the tramway-vehicle (which must have at least two axles) were spaced but a short distance apart, which is unavoidable for transporting systems on account of the narrow curves traversed. Therefore in order to prevent the tramway-vehicle from tipping over and to maintain it always in a horizontal position it would be necessary to make it of a complicated and expensive construction, and in so doing the difficulty of obtaining a sufficiently small separation of the wheels would be still further increased and the weight of the vehicle would be greater. These difficulties are avoided by the employment of an electrically-driven suspended railway whose cars can traverse the heaviest inclines without fear of tipping over and without any change in their construction.

It is likewise incident to the present invention that by the interdependence of the elements making up the combination the electric motors on the carriers may be of very small

power, inasmuch as they have merely to overcome the friction upon the horizontal levels, whereas the work of elevating the carriers is performed by the exteriorly-driven mechanical conveyer. The carriers therefore are not obliged to convey any unnecessary dead-weight over the horizontal levels and are essentially cheaper in their construction than when heavier and more expensive driving-motors are employed.

In the accompanying drawings are shown, in Figures 1 and 2, side views of two forms or modifications of the invention.

Referring to the drawings, *a* indicates the carriers; *b*, the hangers; *c*, the loads; *d*, the rails; *e*, the supply-conductor, and *f* the current-collectors. The two levels between which the loads are to be raised or lowered are connected with each other by an interposed incline extending from A to B. Ranged along this incline is a traveling conveyer *g*, (cable or chain,) which passes over the pulleys *h* and *i*, one of which is located in advance of the beginning of the incline and the other in rear of the end thereof. The lower strand of the conveyer may lie above the trackway, as in Fig. 1, or below the trackway, as in Fig. 2.

One of the conveyer-pulleys *h* *i* is driven mechanically and puts the conveyer in continuous motion in the direction of travel of the carriers. The upper strand is held at a suitable interval from the rail by means of the guide-rollers *k* and *l*.

The carriers are each provided with a gripping or clamping apparatus of any well-known kind for automatic coupling and uncoupling with the conveyer.

A carrier designed to pass up the incline travels up to the point A electrically through the instrumentality of the electric motor actuating its traction-gear. At A the gripper or clamping device engages the conveyer, gripping the same from above, below, or sideways, and couples the carrier to the conveyer. The carrier is then carried up the incline by means of the conveyer. At the point B at the end of the incline the conveyer releases itself from the gripper or clamping device *m*. The conveyer is therefore freed from the cable and is driven on further by its electric motor.

That part of the supply-conductor *e* which lies above the incline is deprived of current by the interposition of insulators *n* *o*, as shown.

Having thus described our invention, what we claim is—

1. A system for forwarding loads, comprising a series of carriers having pivotally-suspended loads, automatic cable gripping and releasing clutches, and electric propelling-motors provided with current-collectors, two sections of suspended trackway at different altitudes, an intermediate and connecting section of suspended trackway of steep incline, and an auxiliary propelling-cable ranged along the said intermediate section and in line with the automatic clutches on the carriers; whereby a continuous and automatic forwarding of the carriers is obtained, from one level to another and up a steep intermediate gradient, while maintaining a vertical suspension of the loads; substantially as described.

2. A system for forwarding loads, comprising a series of carriers having pivotally-suspended loads, automatic cable gripping and releasing clutches, and electric propelling-motors provided with current-collectors, two sections of suspended trackway at different altitudes, an intermediate and connecting section of suspended trackway of steep incline, a supply-conductor having a dead or currentless portion with which the current-collectors remain in touch during their progress along the intermediate section of the trackway, and an auxiliary propelling-cable ranged along the said intermediate section and in line with the automatic clutches on the carrier; whereby a continuous and automatic forwarding of the carriers is obtained, from one level to another and up a steep intermediate gradient, while maintaining a vertical suspension of the loads, and without interrupting mechanical contact of the current-collectors with the supply-conductor; substantially as described.

In witness whereof we have hereunto set our hands in presence of two witnesses.

RUDOLF PFAFFENBACH.
HERMANN MÜLLER.
